UNITED STATES PATENT OFFICE.

WILLIAM J. ROBERTS, OF PAWTUCKET, RHODE ISLAND

THREADING ATTACHMENT FOR SHUTTLES.

1,140,287.

Specification of Letters Patent. Patented May 18, 1915.

Application filed March 5, 1914. Serial No. 822,677.

To all whom it may concern:
Be it known that I, WILLIAM J. ROBERTS, a citizen of the United States, residing at Pawtucket, in the county of Providence and 5 State of Rhode Island, have invented certain new and useful Improvements in Threading Attachments for Shuttles; and I do declare the following to be a full, clear, and exact description of the invention, such 10 as will enable others skilled in the art to which it appertains to make and use the same.

This invention relates to improvements in loom shuttles and more particularly to 15 threading attachments therefor.

The primary object of the invention is to provide a threading device which will be exceedingly simple in construction and efficient in operation and by the use of which a 20 shuttle may be threaded without the necessity of employing any instrument whatever for the purpose of forcing the thread through the guide eyes.

A secondary object is to construct the 25 thread guide in such a manner as to enable it to be readily formed from a single piece of wire.

With the above objects in view, the invention resides in certain novel features of 30 construction and combination herein described and claimed and shown in the drawings wherein:

Figure 1 is a plan view of a shuttle showing the application of my invention thereto; 35 Fig. 2 is a similar view of one end thereof on an enlarged scale; Fig. 3 is a side elevation of the parts shown in Fig. 2; Fig. 4 is a transverse section taken substantially on the line 4—4 of Fig. 2; Fig. 5 is a longitudinal section taken on the line 5—5 of Fig. 2; Fig. 6 is a detail perspective of one 40 of the thread guiding eyes; and Fig. 7 is a similar view of the guiding member employed for guiding the thread into said eyes.

In the accompanying drawings, I have 45 shown a shuttle S including the usual bobbin B which is located in a longitudinal recess R as usual.

For the reception of the threading device 50 constituting this invention, one end of the upper side of the shuttle is recessed as at r, said recess gradually increasing in depth from its outer end and terminating in an upright transverse wall W upon the upper

face of which is secured a fibrous pad P. 55 Communicating with the interior of the recess r and passing through one side of the shuttle S is an opening O which is adapted for a purpose to appear. The side of the shuttle in which the opening O is located is 60 preferably channeled out as shown at C to provide for the housing of parts of the threading device and prevent their engagement with the operating parts of the machine when the shuttle is in use.

Located within the recess r is my improved threading device 1 which is here shown in the form of a single piece of wire bent substantially upon itself to form an elongated loop-shaped guiding finger 2, lying longitudinally within the recess r with its closed end inclined upwardly and its terminal deflected to facilitate the insertion of the thread thereunder. One arm of this loop-shaped guide finger is shorter than the other 70 and its terminal is bent downwardly substantially at right angles as shown at 3 and is embedded within the bottom of the shuttle adjacent the outer face of the wall W while the longer arm of said loop is curved 75 outward and said curved portion 4' passed through and obliquely across the opening O and has its terminal bent inwardly and embedded within the side of the shuttle. The shorter arm of the loop which lies wholly 80 within the recess r is bent downward adjacent the bent terminal thereof, as shown at 4 for the purpose of forming a guide for the thread and causing it to enter a guide eye 5 which is located within the recess r in 85 alinement with the space or eye formed between the bent terminal 3 and the downward bend 4 of the short arm of the threading device guide 1. A second guide eye 6 is located within the opening O in the side wall of the 90 shuttle beneath the outwardly curved portion of the long arm of the guide 1 and in a plane below the plane of the eye 5.

The guide eyes 5 and 6 may be of any suitable formation being open at their front 100 ends, but are preferably constructed of single pieces of wire bent substantially upon themselves and having their free ends twisted to provide attaching shanks, while their folded portions are bent so as to form 105 said eyes, which, by this formation, are left open on their under sides at the front thereof.

With the parts as above described, the operation of the device is as follows: The thread T from the bobbin B is passed beneath the finger 2 and pulled rearwardly. 5 This operation will cause the thread to travel downwardly and outwardly upon the downwardly and outwardly curved portion of said finger and will position it as shown in Fig. 3 (looped around said downwardly and 10 outwardly curved portion). In order to completely pull the end of the thread through the opening O, it is simply necessary for the operator to wipe one of his fingers rearwardly over the portion of the wire 15 which spans said opening, which action will pull the thread to such an extent as to form a loop L (see Fig. 5), which loop may then be grasped to pull the thread and thereby cause it to enter the eye 6 at the side of the 20 shuttle. During this threading operation, the downwardly curved portion 4 of the guiding finger has directed the thread into the innermost guide eye 5 and a further pull on the thread causes it to pass under the 25 outwardly bowed portion 4' of the guide 1 and be directed thereby into the outer guide eye 6 and the threading operation will be complete. Thus it will be seen that I have formed an extremely simple and efficient 30 threading device which may be applied to shuttles of various forms and which will readily and successfully perform the function for which it is designed.

From the foregoing description, taken in 35 connection with the accompanying drawings, the construction and operation of the device will be readily understood without requiring a more extended explanation.

Although I have described my invention 40 with considerable particularity, I do not wish to be limited to details of construction other than those amplified in the appended claim.

Copies of this patent may be obtained for five cents each, by addressing the "Commissioner of Patents, Washington, D. C."

Having thus described my invention, what I claim as new and desire to secure by Letters-Patent is:

The combination with a shuttle having a recess in its upper face at one end thereof and an opening through one of its upright sides communicating with said recess, an open guide eye located in the bottom of said recess near one side of the shuttle, another open guide eye located in the bottom of the side opening of said shuttle in a plane below the plane of said first mentioned eye and disposed in transverse alinement therewith, of a thread guide formed of a single piece of wire bent upon itself intermediately of its ends to form an elongated loop, the closed end of which is inclined upwardly and one arm shorter than the other, the short arm of said loop having its terminal bent downwardly to form an attaching prong for insertion in the bottom of the recess near the guide eye therein, said arm also having a downwardly bent portion adjacent its terminal to form a downwardly opening guide arranged in alinement with said guide eye to direct the thread into said guide eye, the long arm of the loop being bowed outwardly from a point midway its length to its free end, said bowed portion extending obliquely across the side opening of the shuttle and having its free end disposed outside of said shuttle, said arm being disposed above the eye located in said opening and having its terminal formed into an attaching prong inserted in the side of the shuttle at the rear of the opening therein.

In testimony whereof I have hereunto set my hand in presence of two subscribing witnesses.

WILLIAM J. ROBERTS.
